ELASTIC WAIST BAND FOR GARMENTS

Lee J. Sherman, Orange, N. J.

Application July 28, 1936, Serial No. 92,952

1 Claim. (Cl. 2-76)

This invention relates to ladies' garments and particularly to means for fastening garments of the kind wherein the front or outer flap of the garment overlaps the opposite or inner flap, although the invention is not necessarily limited to garments of this kind.

The main object is to provide a neat and simple garment which can be slipped on or off by the wearer as readily as a coat or bath robe, and which will require but two manipulations for fastening it upon the wearer, and when fastened will have the fit and appearance of a tailored dress, skirt or a belted waist.

Another object is to provide an elastic fastener member or connector member so arranged in the garment that it may be adjusted around the waist of the wearer like an ordinary belt and over which the front or outer flap of the garment may be fastened, and whereby the garment may be adjusted to fit any figure neatly and snugly.

The type of garment to which this invention primarily relates is usually fitted with fastening means in the form of ribbons or tapes, which, when correctly positioned and tied, prevent the inner flap from showing beneath the front flap, or of falling out of line.

It has already been proposed to provide a button on the inside flap and a corresponding buttonhole on the outside flap and to button the button on the outer flap over the inner one, but such an arrangement does not allow for any adjustment or give a snug fit.

It has also been proposed to provide a tab or a strap having at its ends a button to co-operate with the button and buttonhole of the garment. As the inner flap is usually buttoned adjacent the hip, the adjustment of the garment about the waist requires a blind search for the button-hole, and which sometimes is quite irritable.

The purpose with the present invention is to overcome the various disadvantages connected with the aforementioned old constructions by substituting for the ribbons, tapes, tubular waist lines or the like, a neat and effective fastening which can be adjusted to suit various sizes of garments, while capable of being readily fastened or unfastened.

In carrying out the objects of the invention an elastic tab or band is provided at the edge of the inner flap and another elastic tab or band is provided at the inside of the outer flap adjacent the hip. Each tab is provided with co-operating fastening means.

Other features and advantages of the inven-

tion will become apparent from the following detailed description given with reference to the accompanying drawing.

In the drawing:

Figure 1 is a front elevation of the garment showing it adjusted on the wearer. 5

Figure 2 is a front elevation showing the garment partially adjusted.

Figure 3 is a cross-section along the line 3—3 of Figure 1. 10

Figure 4 is a view in perspective of the elastic tabs and fastening means according to the invention.

Figure 5 is a view similar to Figure 4 showing a modification of the fastening means. 15

Referring to the drawing, the garment 10 is of the type known as a housedress, and as shown said garment opens at the front, so that the same may be put on in the same manner as a coat. The dress 10 comprises two front flaps 11 and 12. In the modification shown in the drawing the flap 11 extends in a straight line over the full length of the garment, but the flap 12 extends laterally from the front at the waistline 13 and is buttoned over flap 11 at 14, 15 and 16. 20 This construction produces the appearance of a tailored dress. The flap 12 may of course, be buttoned only at one place if desired, the additional buttons being added merely for the purpose of style and appearance. 25

The novel fastening means consist of two elastic straps or tabs 17 and 18. The tab 17 is attached to the edge of the flap 11 at 19, and the tab 18 is attached to the garment at the point 20 at the waistline and adjacent the hip of the wearer. 30

The end 18a of the tab 18 is provided with a buckle 21 provided with a hook 22. The end 17a of the tab 17 is folded back providing a slot 23 which is slipped over the hook 22 when the garment is adjusted thus affording a snug and neat fit. The end 18a of the tab 18 is preferably secured to the buckle 21 permanently by inserting the free end through the slot 24 and sewing it on to the obverse side of the tab 18. 40

The free end instead of being sewed on to the back side of the tab 18 may be provided with a second buckle 25 as shown in Figure 5. This construction permits shortening and lengthening of the tab 18 by varying the distance between the end 18a and the buckle 21. 50

The hook 22 can be fitted with an inwardly projecting portion 26 whereby the slot 23 is maintained more securely. 55

The device herein described provides a fastening which can take the place of the ribbons and tapes heretofore employed and which can be adjusted as to effective length, and is capable of being fastened or unfastened at will and with comfort.

Having described the invention in detail the following is claimed:

A garment of the wrap around type having a blouse portion and a skirt portion and a waistline zone defining said portions, said garment being split longitudinally forming two respectively overlying and underlying front sections, the blouse and skirt portion of the underlying section extending substantially to the center of the body, the edge of the blouse portion of the overlying section extending over and covering the

edge of the blouse portion of the underlying section whereby a single breasted effect is produced, a flap extending laterally from the skirt portion of said overlying section over the opposing skirt portion of said underlying section to the opposite hip, means for fastening said flap to said hip, separate means for adjusting said waistline zone snugly upon the waist of the wearer, said means comprising two elastic bands, one of said bands being secured to the edge of the underlying section and the other band being secured to the inside of the overlying section adjacent the hip of the wearer, means for connecting said bands, said means being so positioned that the bands may be connected adjacent the front 15 of the wearer.
